UNITED STATES PATENT OFFICE.

CHARLES D. MATTISON, OF HASBROUCK HEIGHTS, NEW JERSEY, ASSIGNOR
TO ROBERT M. DONALDSON, OF GREENWICH, CONNECTICUT

FEEDER FOR PRINTING-PRESSES.

SPECIFICATION forming part of Letters Patent No. 643,384, dated February 13, 1900.

Application filed January 15, 1898. Serial No. 666,796. (No model.)

To all whom it may concern:

Be it known that I, CHARLES D. MATTISON, a citizen of the United States, residing at Hasbrouck Heights, in the county of Bergen and State of New Jersey, have invented certain new and useful Improvements in Feeders for Printing-Presses, &c., of which the following specification, taken in connection with the accompanying drawings, is a full, clear, and exact description.

In a patent granted to me March 15, 1898, No. 600,736, I have covered a machine for successively separating sheets of paper from a pile for feeding them to a printing-press or other machine, the separation of the sheets being accomplished by a traveling rotating separator-roll which grasps the sheet at one edge of the pile and rolls over the pile with the sheet and delivers it at the opposite edge of the pile. This pneumatic sheet-separating roll delivers the successive sheets to a traveling sheet-support, from which the sheets are conveyed to the printing-press or other machine by any suitable mechanism.

My present improvements relate chiefly to the structure of the feeding devices which convey the successive separated sheets from a sheet separating and feeding device to the printing-press or other machine.

My invention relates, first, to a novel form of automatically - operating sheet-gripper. This sheet-gripper comprises a traveling flexible band or carrier mounted upon suitable supports, such as pulleys or wheels, which are adapted to continuously change the direction of travel of the band or carrier at one or more points, and one or more rigid sheet-gripping plates or fingers secured at their ends to the traveling band or carrier and extending in the direction of travel of the band or carrier, so that when the rigid sheet-gripping plates or fingers arrive at the supports of the band or carrier the free or unattached ends of said plates or fingers will be deflected outwardly from the supporting band or carrier to form a sheet-receiving space between the plates or fingers and the carrier. Coöperating with this traveling band or carrier and the attached sheet-gripping plates or fingers is a suitable sheet-support, which receives the successive sheets from the sepa-

rating and feeding device and delivers their forward edges into the grip of the gripping plates or fingers. As soon as a sheet is properly received between the gripping plates or fingers and the flexible conveying band or carrier said band or carrier is directed forward in a straight line, causing the unattached or free ends of the gripping plates or fingers to be firmly pressed against it for securely gripping the edge of the sheet. When the gripping plates or fingers arrive at the point of deposit, (at which point the traveling band or carrier is deflected by one of its supports,) they are again deflected from the band or carrier by its change in direction and the sheet is released and allowed to come to rest. It is preferable to provide two endless flexible supporting belts or bands supported upon pairs of pulleys or wheels, preferably sprocket-wheels, each endless band or belt being provided with the same number of rigid gripping plates or fingers correspondingly arranged upon them in order that the forward edge of the sheet will be simultaneously gripped by two of the gripping plates or fingers.

As an improvement on the sheet separating and feeding device covered by my above-named patent I propose to provide a traveling sheet-support in the form of an apron or blanket or a series of parallel cords, tapes, or wires wound upon a roll or a platform or frame, which traveling support is so connected with the carriage of the traveling pneumatic separator-roll (or the movable part of any other form of sheet-separating device) that it will support the sheet in approximately horizontal position as it is fed from the separator until the forward edge of the sheet reaches the gripping-fingers upon the traveling supporting-belts, when said traveling support will be given a slight drop or downward movement to facilitate the withdrawal of the sheet from the traveling sheet-support. The traveling sheet-support is preferably in the form of a traveling apron or blanket having one end attached to a winding-drum and passing around a roller journaled in the traveling carriage and its other end attached to a stationary bar, a cord being wound upon a pulley on one end of the winding-drum and passed under suitable stationary guide-pulleys and

around a guide-pulley on the traveling carriage to cause the apron or blanket to move at the same speed as the separator-roll.

I also provide a novel form of sheet-registering delivery-table which receives and registers the successive sheets as they are delivered from the traveling grippers, and afterward delivers said registered sheets to the cylinder of the printing-press or to any other machine to which the sheets are to be fed. This sheet-registering receiving-table comprises a laterally-movable plate or platform upon which the sheets are successively delivered, a suitable stationary registering-guide extending up at right angles to the surface of the plate or platform, and means for imparting a quick transverse movement to said plate or platform. To insure the movement of the sheet with the registering plate or platform, I provide beneath said plate or platform a suction air-chamber communicating with a suitable air-suction pump through a valved passage controlled by an intermittently-operated automatic valve and having suction openings leading from said chamber to the surface of the registering plate or platform. When a sheet is delivered to the platform, the operating mechanism starts to move it to one side and the automatic valve is instantly opened to exhaust the air beneath the sheet and cause the sheet to adhere to the platform and immediately after said valve is closed to break the suction beneath the sheet. The plate or platform moves transversely until the sheet is registered against the guide, when suitable mechanism comes into play to cause the sheet to be delivered to the printing-press or other machine.

In order that the sheet may be registered at either side, I provide side registering-guides at both sides of the registering plate or platform and provide means for shifting the registering plate or platform toward either side.

My invention consists, further, of novel features of construction which, in addition to the above-mentioned main features, will now be described with reference to the accompanying drawings and will afterward be pointed out with more particularity in the annexed claims.

In said drawings, Figure 1 is a side elevation of a paper-feeding machine constructed according to my invention and representing a printing-press operatively connected therewith, the feeding-machine being driven from the power-shaft of the printing-press. Fig. 2 is a plan view of the same. Fig. 3 is a rear end elevation of the same. Figs. 4, 5, and 6 are detail views representing the pile-retaining fingers and showing the operation of the separator-roll in starting a sheet from the pile. Figs. 7 and 8 are respectively a detail rear elevation and a detail sectional-side elevation of the pile-retaining fingers and their supporting-brackets. Fig. 9 is a side elevation of the forward part of the paper-feeding machine to which the greater part of my in-

vention relates. Fig. 10 is a plan view of the same part of the machine. Fig. 11 is a detail longitudinal sectional elevation of part of the same on a larger scale. Fig. 12 is a detail plan view of the part shown in Fig. 11. Figs. 13, 14, 15, and 16 are detail views of one of my improved sheet-gripping devices. Figs. 17 and 18 are respectively detail side elevation and detail plan of the power-transmitting mechanism for operating my improved feeding mechanism. Figs. 19 and 20 are respectively detail side elevation and vertical sectional views of part of the operating mechanism for shifting the sheet-registering table. Figs. 21 and 22 are respectively detail side elevation and detail plan of one of the sprocket-wheels or pulleys for supporting the endless flexible gripper band or support, these views also illustrating one of the gages or sheet-stops of the printing-press. Fig. 23 is a detail side elevation of part of the driving mechanism shown in Fig. 17 for operating the traveling grippers. Fig. 24 is a detail plan view of same, also showing the upper pair of supporting sprocket-wheels and the means for adjustably mounting them on their operating-shaft. Fig. 25 is a detail side elevation similar to Fig. 21 of one of the lower sprocket-wheels of the gripper mechanism. Fig. 26 is a detail plan view of the same, showing the lower pair of sprocket-wheels adjustably mounted upon their supporting-shaft. Figs. 27 and 28 are respectively a detail vertical sectional view and detail side elevation of one of the upper pair of sprocket-wheels. Figs. 29 and 30 are respectively a detail vertical sectional view and detail side elevation of one of the lower pair of sprocket-wheels. Fig. 31 is a detail sectional view of part of a sprocket-wheel, showing the adjustably-supported tooth or sprocket. Fig. 32 is a detail plan view of a modified form of traveling sheet-support which conveys the sheets from the separator-roll and guides them into the grip of the conveyer-grippers. Figs. 33, 34, and 35 are detail side elevational views of the mechanism illustrated in Fig. 32, these views showing the different positions of this modified form of traveling sheet-support during the operation of receiving a sheet from the separator-roll and delivering it to the traveling grippers. Figs. 36 and 37 are detail plan views of my improved sheet-feeding registering mechanism, illustrating the operation of registering a sheet and showing the preferred form of traveling sheet-support for conveying the sheets from the separator-roll to the traveling grippers. This form of traveling sheet-support is also illustrated in Figs. 9 and 10. Figs. 38 and 39 are detail longitudinal sectional elevations of the mechanisms shown in Figs. 36 and 37, respectively. Fig. 40 is a detail plan view illustrating the suction mechanism of the sheet-registering table for quickly exhausting the air from beneath a sheet to cause the sheet to move with the table. Fig. 41 is a detail longitudinal sectional

view of the same. Fig. 42 is a detail transverse sectional view of the suction mechanism of the registering-table. Fig. 43 is a side elevation of the automatic suction-controlling valve which controls the operation of the suction device of the sheet-registering table. Fig. 44 is a detail longitudinal sectional view of the same. Fig. 45 is a transverse sectional view of the same. Fig. 46 is a detail sectional end elevation of the same. Fig. 47 is a detail sectional end view, on a large scale, illustrating the valve-operating device. Figs. 48 and 49 are transverse sectional views of the valve and valve-casing, showing the valve closed and open. Figs. 50 and 51 are detail vertical sectional views of the suction-chamber of the registering-table, illustrating the operation upon a sheet. Fig. 52 is a detail sectional side elevation of part of my machine, showing the preferred means for operating the traveling apron or sheet-support. Fig. 53 is a plan view of the same mechanism. Figs. 54, 55, and 56 are diagrammatic views illustrating the operation of the same mechanism.

The same letters and numerals of reference indicate the same parts throughout the several views.

I prefer to employ my improvements in connection with a sheet separating and feeding machine such as described and claimed in my above-named Patent No. 600,736, and in order that the machine may be fully understood I have illustrated and will now describe some of the features which are already covered by said patent.

1 is a vertically-adjustable pile-supporting table or platform mounted in the usual way between the upright standards 2. The platform or table 1 has secured to it threaded lugs or nuts, in which operate the vertical table-elevating screws 3 3, which are journaled in the standards 2 in any suitable manner and have keyed to their upper ends the beveled gears 4. (Represented by dotted lines.) Extending across the top of the standards 2 is a rotary shaft 5, carrying beveled gears 6, which mesh with the gears 4 on the screws 3. These parts are also shown by dotted lines. 50 10 is a paper-supporting truck having wheels 11, and 12 represents the pile of sheets upon the truck 10.

13 represents tracks upon the table or platform 1, upon which the truck 10 is run into position beneath the feeding mechanism, which will now be described.

15 and 16 are horizontally-extending side frames suitably secured to the standards 2 and rigidly braced by means of the transverse rods and shafts of the feeder.

A carriage 18 19 is supported between the sideframes 15 and 16, and journaled upon the carriage is the pneumatic separating feed-roll 30, which communicates through a suitable valved passage (not shown) with an air-suction pipe 23. The structure of the separator-roll 30 and its controlling-valve will not

be herein described, as it is fully set forth in my above-named patent. In addition to being journaled in the traveling carriage the feed-roll 30 is provided with cog-gears 70 and 71, the gear 70 being integral with one head of the roll, while the gear 71 is keyed to the journal 31. These gears 70 and 71 are in constant mesh with the rack-bars 72 and 73, which are secured to the inner faces of the side frames 15 and 16, and it will be observed that by reason of the engagement of said gears with the rack-bars the feed-roll is caused to rotate as it reciprocates or travels over the pile of sheets.

To cause the feed-roll to travel over the surface of the pile of sheets, I provide a gear 75 upon the journal 31 of smaller diameter than the gear 71, and meshing with this gear 75 I provide a reciprocating rack-bar 76, which is secured to a dovetailed slide 77, which reciprocates in the dovetailed guide-groove 78 formed in the inner face of side frame 15. To effect the reciprocation of the sliding rack 76, I provide a rotary crank 80 upon the end of a short shaft 234 and connect the crank 80 with sliding rack 76 by means of a pitman 82. The short shaft 234 is operated as hereinafter explained.

90 is the squared end of shaft 234, adapted to receive a crank to enable the operation or change in position of the machine-table and other working parts without power.

95 are arms extending up from the carriage side frames 18 and 19. 96 are slots in said arms in which is a shaft 99, upon which are freely journaled the co-operating auxiliary feed rolls or rollers 100, which operate in peripheral contact with the feed-roll and assist in the feeding operation.

101 are stationary arms having inclined forward ends which are adapted to engage beneath shaft 99 as the carriage nears the rear part of its stroke and raise the auxiliary feed-rolls 100 out of contact with the feed-roll 30.

Extending between the side frames 18 and 19 of the carriage is a rod or bar 105, upon which is supported a stripping-plate 106, the edge of which rests very closely to the periphery of the separating feed-roll and is adapted to direct the edge of the sheet away from the feed-roll to the traveling sheet-support, which I will now describe.

120 125 is a rock-shaft journaled at 126 in the side frames 15 and 16, and 127 are feeler-arms keyed to the shaft 125 and adapted to be intermittently lifted out of engagement with the pile of sheets when the separator feed-roll 125 comes into initial position for separating a sheet. The feeler-arms 127 are brought into engagement with the top of the pile automatically immediately after each sheet is removed by the feeder-roll.

128 is a ratchet-wheel keyed to the outer end of shaft 5, and 129 is an oscillating arm journaled upon shaft 5 and supporting the gravitating pawl 130 in constant engagement

with the ratchet-wheel 128. The rotary shaft 234 has keyed to it a cam 132.

133 is a rod or bar pivoted upon the journal 134 to the oscillating arm 129 and carrying a 5 slotted head or plate 135 at its lower end, which straddles the shaft 234 alongside of the cam 132. An antifriction-roller is journaled upon the head or plate 135 and adapted to be engaged by the cam 132 for causing the longitudinal movement of rod or bar 133 for effecting the movement of the pawl 130 one stroke.

At one end of the rock-shaft 125 is keyed a 10 guide-arm 140, to which is journaled a guide-block 141.

142 is a rod pivoted to the head 135 and extending forwardly and passing through the 15 guide-block 141.

144 is a tappet-collar secured to the rod 142 20 and adapted to engage the block 141 for rocking the shaft 125 and elevating the paper-feeler-fingers from the surface of the pile. The rod 142 also supports an adjustable arm 145, upon which is formed a triangular dog or 25 detent 146, and keyed to the rock-shaft 125 is a rock-arm 147, formed with a similar dog or detent 148 and adapted to engage the detent 146 for regulating the action of the pawl-operating cam.

30 160 is a rock-arm keyed to rock-shaft 125, and 161 is a spring connecting said rock-arm to the machine-frame and acting against the operation of rod 142, holding the guide-block 141 against the tappet 144 and throwing the 35 feeler-fingers 127 into contact with the surface of the pile at the proper time. The above-described feature forms no part of my present invention, and for a fuller description and illustration of such parts reference is made to 40 my said Patent No. 600,736.

The main feature of novelty relating directly to the paper-separating mechanism disclosed in my above-named patent is illustrated in Figs. 3, 4, 5, 6, 7, and 8 of the drawings. 45 This feature of novelty comprises one or more flexible or elastic pile-retaining fingers which are constantly in engagement with the rear edge of the pile for holding the pile intact and preventing the separation of more than one sheet. 200 indicates these fingers, which are preferably formed of soft rubber. The rubber fingers 200 are attached to a block 201, which is pivoted at 202 to the upper end of a bracket 203, which straddles the frame-bar 204 and is rigidly secured thereto by set-screws 205. The block 201 is pivotally mounted in the bifurcated upper end of the bracket 203 and is adjustably secured in position by means of the set-screw 206, which engages one of the 50 side faces of block 201.

The operation of the pile-retaining fingers 200 will be clear from the diagrammatic views Figs. 4, 5, and 6. In Fig. 4 the separator-roll 30 is illustrated coming to a point of rest 60 over the rear edge of the pile of sheets preparatory to separating a sheet. In Fig. 5 the roll is in position, it having pressed down the

rubber retaining-fingers 200. In Fig. 6 the roll is illustrated with the top sheet engaged by the suction-grip in readiness to be stripped 70 from the pile. The next under sheet is partly separated, but is retained by the flexible fingers.

Referring to Figs. 2, 3, 52, 53, 54, 55, and 56, I will describe the preferred form of traveling sheet-support which receives the sheets from the separator-roll 30 and delivers them to the traveling sheet-grippers. 110 represents the traveling blanket or apron, which is attached at one end to the winding-roll 112 and passes rearwardly to a freely-journaled guide-roll 112^a, and then forwardly under the upper working portion of the apron to a bar 112^b, supported between side frames 15 and 16 of the feeder. The end of the apron or blanket 110 is attached to the bar 112^b. The roll 112^a is close to the stripping-plate 106, so that the sheet will pass from the stripping-plate on to the upper working portion of the apron or blanket 110. At one end of the winding-roll 112 I provide a cone winding-pulley 116, around which is wound a cord or cable 117, which is attached at one end to said pulley, is wound thereon, and extends rearwardly therefrom under the guide rolls or pulleys 118 and 118^a, journaled to the side frame 16. Said cord or cable 117 then passes around a flanged roll or pulley 119, journaled to the side frame 18 of the traveling carriage and has its rear end attached to a stationary pin 120 on the side frame 16. It will be observed, particularly with reference to Figs. 52, 54, 55, and 56, that as the separator-roll 30 starts to roll forward with a sheet adhering to it the roll 119, traveling with the feeder-carriage, will cause the cord or cable 117 to unwind from the pulley 116 and the apron or blanket 110 to wind upon the roll 112. This will therefore cause the supporting or working surface of the traveling blanket or apron 110 to travel at the same rate of speed and in the same direction as the sheet which is fed from the separator-roll 30, so that the sheet will be supported and carried along as fast as it leaves the separator. The winding-pulley 116 is made cone-shaped to compensate for the increase in diameter of the roll of the apron or blanket upon the winding-roll 112, so that the speed of the sheet-supporting surface of the apron or blanket will be constant. 115

In the several figures of the drawings I have represented two different devices for supporting the winding-roll 112. In Figs. 2, 3, 52, and 53 the winding-roll 112 is journaled in arms *a*, adjustably mounted in brackets *b*, extending up from rock-arms *c*, journaled upon bolts *d*, attached to the side frames 15 and 16. *e* is a rock-shaft journaled in the side frames 15 and 16, and *f* represents rock-arms keyed to the rock-shaft *e* and connected 125 at their forward ends by links *g* with the rock-arms *c*, which support the winding-roll 112. *h* is an operating rock-arm keyed to one end of the rock-shaft *e* and provided at 130

its forward end with an antifriction-roller h' , which works upon the face of the cam 215, hereinafter described.

In Figs. 9, 10, 36, 37, 38, and 39 I have represented the traveling sheet-support in the form of a series of parallel cords, wires, or tapes 110^a, which have their forward ends secured to the winding-roll 112 and extend rearwardly and are attached to the stripping-plate or its supporting-bar of the traveling carriage. In these figures I do not show the means for winding the roll 112 for keeping the slack of the cords wound upon it, but any suitable means, such as above described, may be employed for this purpose. In this form of the device the winding-roll 112 is journaled in rock-arms 210, mounted upon the rock-shaft 211, supported in journals 212 of the side frames 15 and 16. The rock-arm 210 at the right side of the frame is formed with a slight extension 210^a, in which is journaled a small antifriction-roller 214, which rests upon the cam 215, keyed to a shaft 216, driven as hereinafter explained. The rock-arm 210, with its antifriction-roller 214, takes the place in this form of the device of the rock-arm h and its antifriction-roller h' in the preferred form of the device above described, and the remainder of the description of this part of the mechanism will apply to either form of device.

The purpose of the cam 215 is to intermittently drop the winding-roll 112 and the forward portions of the sheet-supporting apron 110 or cords or tapes 110^a to allow a free and unobstructed passage of the sheets after they have been gripped by the improved traveling grippers.

220 is an inclined worm-shaft journaled at its upper end in bearings 221 and at its lower end in the bearings 222. Keyed to the lower end of the worm-shaft 220 is a bevel-gear 223, which meshes with a similar bevel-gear 224, keyed to a short shaft 225 in the printing-press frame. At the opposite end of the short shaft 225 is keyed a small cog-gear 226, which meshes with a large gear 227, keyed to one end of the power-shaft 228, journaled in the printing-press frame and driven by any suitable motive power—such, for instance, as the electric motor 230 illustrated in Fig. 3.

232 is a worm keyed to the upper end of the shaft 220 between bearings 221, and 233 is a worm-wheel keyed to a shaft 234. The shaft 234 and shaft 216 are journaled at their inner ends in the side frame 15 and at their outer ends in the auxiliary bracket-frame 235, secured to said side frame. Keyed to the outer end of the shaft 234 is an oval cog-gear 236, which meshes with its mated oval cog-gear 237, keyed to the outer end of the shaft 216. The shaft 216 also carries adjacent to the side frame 15 a cog-gear 238, which meshes with a smaller cog-gear 239, keyed to the journal end of the sprocket-wheel-supporting shaft 240. By this means the shaft 240 is driven from the worm-shaft 220, the shaft 240 in turn operating the traveling grippers, hereinafter more

fully explained. The purpose of the mated oval cog-gears 236 and 237 is to cause the traveling grippers to assume a very slow speed at the point of transfer of the sheets from the traveling sheet-support to the grips and at the point of delivery of the sheets upon the sheet-registering platform or table, as herein-after explained. A sheet is delivered upon the registering-platform by one pair of grips about the same moment that the succeeding sheet is taken from the traveling sheet-support by the following pair of grips.

250 is the frame of a printing-press of any suitable construction, illustrated to be of the flat-bed type.

251 is the rotary impression-cylinder, provided with the usual sheet-grippers 252.

253 is the reciprocating form, represented as a lithographic stone, and 254 indicates the inking-rolls.

255 are the sheet-delivery tapes of the printing-press, and 256 the usual delivery fly-frame.

257 is the delivery-table, arranged to receive the printed sheets.

258 is one of a pair of rods coupling the press-frame to the feeder-frame for the purpose of rigidly bracing them.

260 is an inclined table or platform supported above and upon the printing-press frame 250.

261 indicates two trussed arms journaled upon pins 262 at the lower forward end of the inclined table 260. These arms 261 support in their lower forward ends the upwardly-extending bracket-arms 265. The bracket-arms 265 are journaled at 266 and are formed with inclined bifurcated upper ends 267, in which are supported the journal ends 268^a of the transversely-extending sprocket-wheel-supporting shaft 268. The journal end 268^a of shaft 268 is adjustably mounted in the bifurcated upper end of the bracket-arms 265 and is supported in any adjusted position by means of set-screws 269 and 270, engaging the journal above and below.

271 is a set-screw threaded in bracket 272 of each arm 261 and engaging one of the bracket-arms 265 for adjusting it longitudinally of the direction of feed. These adjustments are for the purpose of bringing the traveling sheet-grippers in proper relation to the feed-table and cylinder of the press and for holding the traveling flexible bands or supports of the grippers under proper tension.

275 are the intermittently-operating sheet stops or guides of the printing-press, having spring-arms 276 of ordinary construction.

This brings me to a description of my improved traveling sheet-grippers. These grippers consist, essentially, of a traveling flexible support having secured to it one or more rigid plates or fingers, said fingers extending longitudinally of the flexible support and said flexible support being provided with means for continuously changing its direction

of travel at one or more points for slightly deflecting or separating the free ends of the rigid plates or fingers at such points to receive or deliver a sheet.

- 5 280 indicates one of a pair or series of endless flexible bands constituting the traveling flexible support of my improved grippers. The bands 280 are supported upon the wheels or pulleys 281 and 282, the pulleys or wheels 10 281 being suitably keyed to the forward shaft 268, while the pulleys or wheels 282 are keyed to the rear shaft 240. It is preferred to employ sprocket-wheels for the supporting wheels or pulleys 281 and 282, and to enable 15 the flexible traveling band 280 to operate upon the sprocket-wheels it must be formed with perforations at proper intervals to fit over the sprockets. The preferred construction and arrangement of the sprocket-wheels and 20 their supporting-shafts will be more particularly referred to presently.

The rear sprocket-wheel-supporting shaft 240 is mounted in suitable adjustable bearings 241, which rest in openings 242, formed 25 in the bracket extensions 243 of the side frames 15 16.

245 are set-screws threaded in the brackets 243 and engaging the adjustable bearings 241.

Referring now to Figs. 23 to 31, both inclusive, I will describe the preferred structure 30 of the sprocket-wheels and their supporting-shafts.

As illustrated in Figs. 27, 29, and 31, I prefer to form the sprocket-wheels of suitable 35 wheels having radial openings x , extending through their rims and receiving sprocket-pins y , formed with cylindrical ends, and a contracted cylindrical neck extending between the cylindrical ends. These sprocket-pins y are secured in the radial openings x by 40 means of set-screws z , threaded into the inner annular flange of the rim and engaging the contracted portion of the sprocket-pin y . The purpose of this construction is to enable 45 the perfect adjustment of the sprockets of the wheels and to provide a safeguard against the chance of a sprocket-pin dropping out and falling into some part of the machine. If the set-screw z should become loose, the 50 sprocket-pin y would drop until the shoulder of the cylindrical head or end engages the pin y , and said pin y would not be allowed to fall out of its socket.

It will be observed from Fig. 24 that shaft 55 240 is provided with two longitudinally-extending feathers or keys 240^a and a central bearing-sleeve 249. The sprocket-wheels 282 are mounted upon the shaft 240 and are formed with spline-grooves 282^a, which engage the 60 feathers or keys 240^a. Each sprocket-wheel 282 is also formed with a screw-threaded opening 285. 290 is a screw centrally journaled in the bearing-sleeve 249 and having its screw-threads extending oppositely from the center. 65 The outer ends of the screw 290 are journaled in bracket-arms 291, supported from the journal ends of shaft 240, and the projecting ends

of the screws are formed with squared ends 290^a for the reception of the crank or hand wheel. By the rotation of the screw 290 from either side of the machine it will be observed that the sprocket-wheels 282 will be moved inwardly simultaneously the same distance. I arrange a scale 293 on the shaft 240 to enable me to properly determine the position 70 75 the sprocket-wheels are to assume.

Referring to Figs. 25, 26, 29, and 30, it will be observed that the lower sprocket-wheels 281 are similarly formed with spline-grooves 281^a and threaded openings 295. The sprocket-wheels 281 are mounted upon the shaft 268, which shaft is provided with the feather-keys 268^a, with which the grooves 281^a engage. 80 85 296 is a journal-sleeve centrally supporting an adjusting-screw 297, which passes through the threaded openings 295 of the sprocket-wheels 281 and has its outer ends journaled in the bracket-arms 298, supported upon the journal ends 268^a of the shaft 268. 297^a are the squared ends of the adjusting-screw 297. 90 95 299 is a scale upon the shaft 268. The sprocket-wheels 281 are simultaneously adjusted upon their supporting-shaft in the same manner as the sprocket-wheels 282, and it will be observed that by reason of the scales on the 95 sprocket-wheel-supporting shafts both sets of sprocket-wheels can be adjusted to the corresponding positions upon their shafts with accuracy.

As above stated, the improved traveling 100 gripping mechanism, of which I have so far described the flexible supporting-bands and their supporting and driving sprocket wheels or pulleys, comprises said flexible traveling bands, with rigid gripping plates or fingers 105 secured to it. 300 refers to the improved rigid gripping plates or fingers, which gripping plates or fingers are represented more particularly in Figs. 13, 14, 15, and 16. It will be observed that each of these rigid plates or 110 fingers is formed of rigid sheet metal, with integral ears 301 cut from it and bent at right angles to the plate to form sheet-registering stops or shoulders and a transverse undercut 300^a between the registering-ears and the 115 forward gripping portion of the plate or finger. Each gripping plate or finger 300 is secured to the traveling supporting-band by set-screws 302, which pass through the band and the plates, engaging the plates or fingers 120 at such points that they will be rigidly secured to the band adjacent to one end only and will allow the opposite end to be free in order that said free end may be separated slightly or deflected from the supporting-band to receive or deposit a sheet. The purpose of the undercuts 300^a is to allow ample room for the free entry of the leading end of the sheets to the registering-ears and insure the ready release of the sheets when the gripping plates are deflected in delivery position. 125 130

In Figs. 13 and 15 the band 280 is shown slightly deflected from a straight line, and the gripping-plates are slightly separated

from the band to form a sheet-receiving space between them. In Fig. 16 the band 280 is shown straight, with the gripping plate or finger held firmly against it for grasping a sheet.

5 This operation of my traveling grippers will be more fully understood from a description of the mechanisms which coöperate therewith. It will be observed that between the pivoted arms or frame-pieces 261 is mounted 10 the forward portion of the inclined feed-table, over which the sheets are passed to the printing-press. This forward inclined portion of the feed-table is constructed to form a sheet-registering plate or platform. 260^a is the 15 base plate or support of the forward portion of the table, and 310 and 311 are two plates supported upon the base 260^a, with a space between them for the accommodation of an adjustable sheet-registering guide hereinafter referred to. The registering-plates 310 and 311 are connected by arched yokes 312, which are rigidly secured to the plates at their edges, so that the two plates will move as a whole and constitute a laterally-movable 25 sheet-registering platform. The rear or upper edge of the registering-plate 310 is beveled off and is engaged by a securing guide-plate 313, which is attached to the base-plate 260^a and overlaps the beveled portion of plate 310. The rear edge of the guide-plate 313 is 30 curved downwardly, so as to avoid the possibility of interfering with the forward passage of the sheets thereover. 315 indicates transversely-extending oblong slots cut through 35 the plates 310 and 311, and 316 indicates vertically-extending guide-blocks which are attached to the base-plate 260^a and extend up through the slots 315 to guide the laterally-moving sheet-registering plate or platform 40 formed of the plates 310 and 311. It will be observed that the contiguous edges of the plates 310 and 311 are beveled to avoid abrupt edges. Between the contiguous edges of plates 310 and 311 is formed a transverse 45 slot or depression exposing the base-plate 260^a, and in the base-plate 260^a along this exposed portion is formed a series of openings 360 to support a changeable sheet-registering guide. The sheet-registering guide, 50 which is probably best illustrated in Figs. 10, 11, 40, and 41, comprises a base-plate 365, formed with one or more circular lugs or pins (not shown) depending from its lower face and adapted to engage in one or more 55 of the openings 360 in base-plate 260^a. Projecting up from the top face of the registering-plate 365 are the integral lugs 365^a, through which passes an adjusting-screw 366, carrying at its forward end a registering-guide 367 and provided with an operating thumb-nut 368. When the registering-guide has been set to the approximate position by placing the retaining pins or lugs in engagement with the proper openings 360, it 60 will be clear that the registering guide-plate 367 can be adjusted to a nicety by the manipulation of the adjusting-screw 366. The

sheet-registering device can be placed at either side of the registering-table, and by reason of the slotted rock-arm 327 the registering-platform 310 and 311 can be shifted toward either side. It will be clear that by loosening the nut which clamps the pin 326 in the slotted lever 327 said pin 326 can be shifted to the opposite end of the lever 327, 75 which will cause the plate to be shifted toward the opposite side of the platform. It will be observed that the yokes 312 span the opening between the plates 310 and 311, thereby allowing the registering-plate 365 to be placed 80 at the extreme edge of the supporting base-plate 260^a.

To register the sheets against the guides above referred to, I connect the plate 310 with the long arm of a bell-crank lever 320 by 85 means of a link 321, journaled to a bracket 322, secured to plate 310. The bell-crank lever 320 is journaled at 323 upon a bracket extending from one of the arms 261, and the short arm of said bell-crank lever 320 is connected with a rod 325, which extends rearwardly and is journaled at its rear end upon a bolt 326, which is adjustably mounted in a slotted rock-arm 327. The rock-arm 327 is formed with an elongated slot extending from 90 end to end and with a yoke-support 328, which is journaled upon a pin 329. The pin 329 is concentric with the journal 262, which supports the arm 261 at the right-hand side of the machine. The lower end of the slotted 95 rock-lever 327 has pivoted to it the forward end of a rod 330, which extends rearwardly and is journaled to a short rock-lever 331, which carries an antifriction-roller 332, working in a face-cam 333, keyed to the shaft 234 inside 100 of the bracket 235. By the rotation of cam 333 it will be observed that the sheet-registering table 310 and 311 will be given an intermittent lateral movement, and that therefore the sheet which has been deposited upon 105 the registering plates or platform, will be caused to move sidewise against the vertical sheet-registering guide.

To insure the movement of the sheet with the registering-table, I have provided a suction device which will suck the air from beneath the sheet just prior to the registering movement of the platform. When the machine is operating slowly, it will not be necessary to employ this suction device, as the 115 sheet will have sufficient time to settle upon the platform before it is registered. In rapid work, however, it is essential that the sheet should immediately settle to the sheet-registering platform, and for this purpose I provide beneath the plate 310 a suction air-chamber 340, which has an opening 341 communicating with the pipe 342, which leads to the inlet-port 343 of a valve-casing 344. The suction air-chamber 340 communicates through 120 openings 340^a with the surface of the sheet-registering plate or platform. Within the valve-casing 344 is a cylindrical valve-plug 125 345, formed with a series of radial ports or

passages 345^a and a central opening or cavity 345^b, which is in constant communication with the exit-port 346, from which a pipe 347 leads to a suction air-pump or other suitable device adapted to exhaust the air therefrom. The rotary valve-plug 345 is keyed to its supporting-shaft 348, which is journaled in the casing 344 and in a bracket-arm 349, secured to one of the pivoted arms 261. The valve-casing 344 is rigidly mounted upon a bracket 350, said bracket being also attached to or formed integral with the arm 261. Also keyed to the shaft 348 of the valve-plug is an operating-disk 351, formed with a series of radial notches 351^a. 352 is an oscillating arm freely journaled upon the shaft 348 between the disk 351 and casing 344, and 353 is a dog or pawl journaled upon a pin 354, attached to oscillating arm 352, and supported thereby in proper relation to the operating-disk 351 to engage the notches 351^a, and thereby impart a partial rotation to the valve-plug 345. It will be observed from Fig. 47 of the drawings that the dog 353 is formed with two engaging noses in order that it may be reversed for operating the valve in either direction. The oscillating arm 352 is provided with a pin 355, which is engaged by the lower bifurcated end 356 of an arm 357, formed integral with or attached to the link 321, which connects the registering-table with its operating bell-crank lever. By this connection it will be observed that when the operating mechanism starts to move the registering-table laterally the arm 357 will immediately operate the oscillating arm 352 and cause the valve-plug 345 to be moved sufficiently to open up communication between the exit-port 346 and inlet-port 343 of the valve-casing. The result of this will be an instantaneous exhaust of the air from the suction-chamber 340. If the sheet has just been deposited upon the registering table or platform 310 311, it will probably rest, as indicated in Fig. 50, with air beneath it, and the instant the air is sucked from the chamber 340 it will be clear that the air will also be withdrawn from beneath the sheet upon the table, and this will cause the sheet to lie flat upon the platform or table and adhere thereto, so that it will move with the table and be registered against the registering-guides. It would not be desirable to have the suction device continue to hold the sheet upon the table while it is being registered, because it could not then slide when it engages the registering-guide and would consequently be buckled and would not be accurately registered. To prevent this constant suction upon the sheet on the table, it will be observed that I arrange the valve-plug 345 in its casing in such position that the communication will be instantly made and cut off. As seen in Fig. 48, the communication is cut off, but one of the valve-ports 345^a is very close to the casing-port 343, so that the first part of the movement of the valve-plug will open up communication for an instant and

immediately close the communication, the continued movement of the valve-plug during the registering movement of the table serving to bring the succeeding port 345 close to the port 343 in readiness for the next initial exhaust of the air from beneath the succeeding sheet.

When it is desired to move the sheet-registering plate or platform and the traveling sheet-grippers away from the impression-cylinder of the printing-press, it is only necessary to adjust the pin 326 of connecting-rod 325 to the pivotal center of arms 261, when the arms 261 can be moved vertically on their journals for throwing the forward parts of the feeding mechanism up out of the way.

In Figs. 32 to 35 I have illustrated a modified form of traveling sheet-support which co-operates with the pneumatic sheet-separating roll and I will give a brief description of this modification. 400 indicates one of a pair of track-bars attached to the side frames 15 and 16 of the feeder and extending toward the shaft 240 of the traveling gripper mechanism, the portion of the track-bars directly beneath the shaft 240 being dropped or inclined, as indicated at 400^a. 401 indicates one of a pair of side bars which are pivoted at 402 to lugs extending forwardly from the traveling carriage which supports the pneumatic separator feed-roll. The side bars 401 have downwardly-projecting legs 403, which carry in their lower ends antifriction-rolls 404, which travel upon the tracks 400. 405 is a sheet of aluminium or other suitable metal, which is supported upon the frame-bars 401. It will be observed from Figs. 33, 34, and 35 that the sheets of paper are passed by the feed-rollers on to the traveling plate or platform 405, by which said sheets are supported until the forward edge comes into position to be grasped by the traveling sheet-grips. 410 indicates one of a pair of deflector plates or guides which are supported directly behind the rear sprocket-wheels 282 in position to direct the forward edge of the sheet into the mouth of the grips, the deflector-plates 410 being supported a sufficient distance in the rear of the traveling grippers to allow their free passage.

The operation of my improved feeding-machine may be briefly described as follows: By the operation of the sheet-separator roll 30, as fully explained in my above-named patent, the sheets are simultaneously separated from the pile 12 and delivered to the traveling sheet-support. The moment the forward edge of the sheet approaches the point of delivery to the traveling grips the forward end of the traveling sheet-supports (whether it be the apron, series of cords or tapes, or the traveling supporting plate or platform) is dropped by the controlling-cam or the inclined portion of the track and the edge of the sheet is deflected into the open mouths of two corresponding gripping plates or fingers carried upon the traveling flexible

band 280. At the point of this transfer from the traveling sheet-support to the traveling grippers the grippers are traveling at a slightly-slower speed to insure the registering of the forward edges of the sheets with the ears 301 of the gripper-plates. Immediately after the sheet has been placed into the grips the direction of travel of the band 280 is in a straight line, which will cause the 5 grips to firmly clasp the sheet against the supporting-band. The sheet is carried forward over the inclined platform 260, the forward end of the traveling sheet-support having dropped out of the way to allow it to pass 10 freely therefrom. When the forward edge of the sheet reaches the gages 275 of the printing-press, the bands 280 will have started around the supporting-pulleys 281, which will cause the gripper-plates to be deflected from 15 the band and release the sheet therefrom to rest momentarily upon the side registering table or platform 310 and 311. The moment the sheet is being delivered from the grips, the grips are again running at a very slow 20 speed in order to avoid buckling or rumpling the forward edge of the sheets against the guides of the printing-press. Every time the traveling grips slow down a sheet is delivered from one pair of grips to the registering-platform 25 and another sheet is taken by the succeeding pair of grips from the traveling sheet-support. Immediately after the sheet is dropped upon the registering plate or table the operating mechanism of said registering 30 plate or table comes into action first to suck the air from beneath the deposited sheet and next to move the sheet over against the registering guide-plate 367. As soon as the sheet is properly registered in this manner the printing-press guides 275 are lifted and the cylinder-grippers 252 of the printing-press engage 35 the sheet and carry it into the press. The sheet after being printed in the usual manner is delivered by the fly 256 upon the table 257.

Having thus fully described my invention, the following is what I claim as new and desire to secure by Letters Patent:

1. In a sheet-feeding machine, the combination of a flexible traveling support, with a rigid sheet-gripping plate or finger attached at one end to said flexible support, means for deflecting the flexible support for causing the free end of said plate or finger to slightly separate or be deflected from the flexible support, and a stop limiting the entry of sheets into the bite of the sheet-gripping plate or finger, substantially as set forth.

2. In a sheet-feeding machine, the combination of a traveling flexible support or carrier, with a rigid sheet-gripping plate or finger attached at one end to said flexible support, a stop mounted upon the carrier limiting the entry of sheets into the bite of the sheet-gripping plate or finger, and means deflecting the flexible support or carrier at one or more points for causing the free end of

said plate to be slightly deflected or separated from its flexible support to receive or release sheets, substantially as set forth.

3. In a sheet-feeding machine, the combination of a traveling flexible support or carrier having a rigid sheet-gripping plate or finger attached at its end thereto, with means for deflecting the free end of the gripping plate or finger at one or more points, and a stop formed on or attached to the gripping plate or finger and limiting the entry of sheets into the bite of the gripping plates, substantially as set forth.

4. In a sheet-feeding machine, the combination of an endless flexible band, suitable supporting wheels or pulleys upon which said band is supported, and a rigid sheet-gripping plate or finger formed with registering ears 85 or lugs, said rigid plate or finger being securely attached at one end to the flexible band, substantially as set forth.

5. In a sheet-feeding machine, the combination of a plurality of endless flexible bands, 90 suitable supporting wheels or pulleys for supporting said endless bands, a series of rigid plates or fingers attached at intervals to said endless flexible bands, each rigid plate or finger having two registering ears or lugs which 95 extend at right angles from the plate or finger transversely to its supporting-band, and means for feeding sheets of paper to said gripping plates or fingers, substantially as set forth.

6. In a sheet-feeding machine, the combination of a plurality of flexible traveling bands or supports, with a plurality of rigid plates or fingers attached to said flexible bands or supports at corresponding intervals, each 105 of said rigid plates or fingers being formed with a pair of registering ears or lugs which extend transversely of the supporting-band, means for deflecting the flexible band or support at proper points, and means for feeding 110 sheets of paper to the grips formed by said rigid plates upon the flexible supports, substantially as set forth.

7. In a sheet-feeding machine, the combination of a plurality of endless flexible bands, 115 suitable supporting wheels or pulleys for supporting said endless bands, rigid sheet-gripping plates or fingers formed with approximately right-angular sheet-registering ears or lugs, said plates or fingers being rigidly secured at their ends to the endless bands, means for driving said wheels or pulleys, suitable sheet-feeding means arranged to deliver sheets to the grippers upon the endless bands, and means for driving said sheet-feeding 125 means at a faster rate than the endless bands, whereby sheets will be accurately placed in the grippers, substantially as set forth.

8. In a sheet-feeding machine, the combination of a plurality of flexible traveling bands or supports, with a plurality of rigid plates or fingers attached to said flexible bands or supports at corresponding intervals, means 130 for deflecting the flexible band or support at

proper points, a stop limiting the entry of sheets into the bite of the grips formed by said rigid plates upon the flexible supports, and means for feeding sheets of paper to the grips, substantially as set forth.

5. In a sheet-feeding machine, the combination of a flexible traveling support, with a rigid sheet-gripping plate or finger, such as 300, having an undercut 300^a, and attached 10 at one end to the flexible support, and means for deflecting the flexible support for causing the free end of said plate or finger to slightly separate or be deflected from the flexible support to receive or release sheets, substantially as set forth.

15. In a sheet-feeding machine, the combination of a flexible traveling support, with a rigid sheet-gripping plate or finger, such as 300, having an undercut 300^a and attached 20 at one end to said flexible support, means for deflecting the flexible support for causing the free end of said plate or finger to slightly separate or be deflected from the flexible support, and a stop limiting the entry of sheets 25 into the bite of the sheet-gripping plate or finger, substantially as set forth.

10. In a sheet-feeding machine, the combination of a traveling flexible support or carrier having a rigid sheet-gripping plate or finger attached at its end thereto, said plate or 30 finger having an undercut such as 300^a for the purpose specified, with means for deflecting the free end of the gripping plate or finger at one or more points, and a stop formed on or attached to the gripping plate or finger and 35 limiting the entry of sheets into the bite of the gripping-plates, substantially as set forth.

12. In a sheet-feeding machine, the combination of a sheet-separating device, with a 40 traveling sheet-support receiving the sheets from the separating device, a traveling flexible band or support having rigid sheet-gripping plates or fingers secured to it, and means for lowering or dropping the traveling sheet-support at the point of transfer therefrom to the sheet-gripping plates, substantially as and for the purpose set forth.

13. In a sheet-feeding machine, the combination of a sheet-separating device, with a 45 traveling sheet-support adapted to receive the sheets from the separating device and supported at the point of deposit upon a suitable roll, rock-arms in which said roll is journaled, a cam adapted to elevate and lower the roll, and traveling sheet-grippers adapted to receive the sheet from said traveling support, substantially as set forth.

14. In a sheet-feeding machine, the combination of a traveling sheet-separating device, 50 with a winding-roll journaled in suitable bars, a guide-roll journaled upon the carriage of the separating device, an apron or blanket attached at one end to the winding-roll and extending over said guide-roll and attached at 55 its other end to a stationary point, and suitable means connecting the traveling carriage

of the separator with the winding-roll to cause the sheet-supporting apron or blanket to travel at the same speed as the separating device, substantially as set forth.

15. In a sheet-feeding machine, the combination of a traveling sheet-separating device, with a traveling sheet-support comprising a winding-roll having a pulley at one end, a blanket or apron attached at one end to the 70 winding-roll and at its other end to a stationary bar, a freely-journaled guide-roll journaled in the carriage of the traveling separating device over which guide-roll the apron or blanket extends, a cord or cable wound upon the pulley of the driving-roll and extending around suitable guide-pulleys and attached at its other end to a stationary point, and a freely-journaled guide-pulley journaled to the carriage of the separating device and 80 engaging a cord or cable between the stationary point and one of the guide-rolls, substantially as set forth.

16. In a sheet-feeding machine, the combination of a transversely-movable registering platform, means for moving said platform, a suitable sheet-guide against which the sheet is registered, means for causing the sheet to momentarily adhere to the registering-platform, and means for feeding sheets thereto, 90 substantially as set forth.

17. In a sheet-feeding machine, the combination of a sheet-receiving platform, a suitable sheet-registering guide, means for feeding a sheet to said platform, means for moving the platform transversely, suction-openings in the platform, and means for exhausting the air from said suction-openings to cause the sheet to momentarily adhere to the platform, substantially as set forth.

100 18. In a sheet-feeding machine, the combination of a sheet-receiving platform, a sheet-registering guide, means for feeding the sheet to said platform, means for moving the platform transversely, a suction-chamber communicating with openings extending through the platform, means for exhausting the air from said suction-chamber, and a valve controlling the exhaust of air therefrom, substantially as and for the purpose set forth.

11 19. In a sheet-feeding machine, the combination of a sheet-receiving platform, a sheet-registering guide, means for feeding the sheet to said platform, means for moving the platform transversely, a suction-chamber communicating with openings extending through the platform, means for exhausting the air from said suction-chamber, and a valve operated by the means which move the platform transversely, said valve controlling the exhaust of air from said chamber, substantially as set forth.

11 20. In a sheet-feeding machine, the combination of a sheet-receiving platform, a suitable sheet-registering guide, means for feeding a sheet to said platform, operating mechanism for laterally moving the platform, a

5 suction-chamber beneath the platform communicating through openings which extend through the platform, means for exhausting the air from said suction-chamber, and a valve controlling the exhaust of air from said chamber, said valve being operated by the platform-operating mechanism, substantially as set forth.

10 21. In a sheet-feeding machine, the combination of a sheet-receiving platform, a sheet-registering guide, means for feeding a sheet to said platform, operating mechanism for laterally moving the platform, a suction-chamber beneath the platform communicating with the surface thereof through suitable openings, means for exhausting air from said suction-chamber, a rotary valve controlling the exhaust of air, a disk upon the valve-stem and an intermittently-operating dog adapted 15 to engage the disk, substantially as set forth.

20 22. In combination with a sheet-feeding machine, a gripper-carrying band, a sprocket-wheel formed with radial openings x in which are adjustably mounted the headed sprocket-pins y having contracted central portions engaged by set-screws z , substantially as set forth.

25 23. In a sheet-feeding machine, the combination of a sheet receiving and registering platform comprising plates 310, 311 united by yokes 312, a sheet-registering guide adjustably supported between the plates 310 and 311, means for operating the registering plate

or platform, means for feeding sheets thereto, substantially as set forth.

35

24. In a sheet-feeding machine, the combination of a platform over which the sheets are fed, said platform having a forward portion which is pivotally mounted upon the rear portion, traveling flexible bands mounted upon sprocket-wheels or pulleys, supports for the rear sprocket-wheels rigid with relation to the rear portion of the platform, supports for the forward sprocket-wheels or pulleys extending up from the forward pivotally-mounted portion of said table, and grippers carried by said flexible bands, substantially as set forth.

40

25 25. In a sheet-feeding machine, the combination of a support for a pile of sheets, and a device for raising the edge of the top sheet and separating and removing said sheet from the pile, with one or more flexible pile-retaining fingers projecting over the top of the pile at one edge and held in constant engagement with the edge of the pile, said retaining-fingers being constructed to yield laterally when the top sheet is separated and subject the under sheets to frictional resistance at their edges, whereby the under sheets will be held 50 back when the top sheet is removed, substantially as set forth.
